MOTOR COACH

Roland E. Gegoux, Pontiac, Mich., assignor to General Motors Corporation, Detroit, Mich., a corporation of Delaware

Application November 3, 1954, Serial No. 32,936

Term of patent 14 years

(Cl. D14—3)

The dominant features of my design are shown in solid lines in each of the above figures.

I claim:

The ornamental design for a motor coach, substantially as shown and described.
